UNITED STATES PATENT OFFICE.

COMMODORE P. BAKER, OF LINCOLN, MISSOURI, ASSIGNOR OF ONE-HALF TO A. W. BAKER, OF BROOKFIELD, MISSOURI.

SWITCH-POINT CONNECTOR.

1,194,121.

Specification of Letters Patent.

Patented Aug. 8, 1916.

Application filed January 7, 1916. Serial No. 70,816.

To all whom it may concern:

Be it known that I, COMMODORE P. BAKER, a citizen of the United States, residing at Lincoln, in the county of Benton and State 5 of Missouri, have invented new and useful Improvements in Switch-Point Connectors, of which the following is a specification.

This invention relates to a switch point connector, contemplating the provision of a 10 rod or bar for connecting the rails of a switch point for movement in unison.

The primary object of the invention is to provide a connector which is adapted for coupling switch rails varying in width or 15 distance between each other, or for adjustable connection with the rails to compensate for wear and maintain the required distance between the switch rails for an accurate and certain switch closing action.

20 A further object of the invention is to provide a rod or bar having means for adjustable connection with the switch rails, which means is adapted to be firmly applied 25 to clamp the rails in proper relative position.

The invention consists of the features of construction, combination and arrangement of parts herein fully described and claimed, 30 reference being had to the accompanying drawing in which:

Figure 1 is a top plan view showing the application of the invention to the switch rails. Fig. 2 is a view in side elevation of the connecting rod and showing the rails in 35 cross section. Fig. 3 is a vertical longitudinal section through one end of the rod and the fastening means and showing the rail in cross section. Fig. 4 is a vertical transverse section on line 4-4 of Fig. 3. 40 Figs. 5, 6 and 7 are detail perspective views of one end of the rod, the tooth clamping jaw and the channeled retaining cuff.

Referring to the drawing, 1 and 2 designate the point rails of a switch, and 3 my 45 improved rod or bar connecting the same for movement in unison. As shown, the rod or bar 3 is provided with a central portion 4 of major depth or thickness, and from which extend the end portions 5 which are of some- 50 what less depth or thickness, the lower face of the bar being, however, continuous in the same plane throughout, so as to adapt the same to move clear of all underlying por-

tions in the track bed. The outer extremities 6 of the end portions 5 form seats for 55 the bases of the rails 1 and 2, and are provided with openings 7 and 8 respectively for connection with suitable switch actuating connections. (Not shown.)

Between the central portion 4 and each 60 extremity 6 each end portion 5 is provided with a longitudinally tapered locking portion 9 provided with a row of transverse parallel locking teeth 10 and an oblong rectangular bolt 11, disposed centrally of the 65 toothed surface and provided with a screw stem 12 formed with a transverse opening 13. The toothed surface or locking portion 9 is adapted for interlocking connection with a clamping plate or member 14. This plate is 70 of oblong rectangular form and provided upon its underside with transverse V-shaped teeth to interlock with the teeth 10. At its outer end the plate 14 is provided with an upright flange or jaw 16 to bear against the 75 inner side of the web of the rail, said jaw having openings 17 therein for the passage of bolts 18 connecting the same with the rail. The body of the plate 14 is provided with an oblong rectangular slot or opening 80 20 to receive the lug or boss 11, whereby said plate is slidably connected with the rod and held from lateral displacement.

It will be evident that by the adjustable connection between the connecting plates 85 and the connector bar said plates may be arranged to suit the distance between the rails 1 and 2, in the use of rails which vary to a greater or less extent from normal in thickness, and that said plates may also be ad- 90 justed on the rod as occasion may require to compensate for variations in the distance between the rails due to looseness from wear or other causes, so that a certain and positive closing of the switch point may be ef- 95 fected. When the rail is applied in position between the clip and clamping plate, it will be evident that it will be held securely against disconnection, so that the required distance between the rails may be main- 100 tained, while at the same time admitting of adjustment at any time to compensate for any looseness due to wear which may develop.

For the purpose of holding the parts more 105 firmly and securely in position, I provide a

channeled or inverted U-shaped cuff or sleeve 20 which is provided with an opening 21 for passage of the screw stem and is adapted to be fitted down upon the body of the plate 14 and sides of the locking portion 9 to coöperate with the boss or lug to hold the plate against any tendency to shifting movement laterally of the rod due to the movements of the parts of the road bed and 10 to the jars and vibrations to which the track structure is subjected. This cuff is engaged by a nut 22 which bears thereon and engages the screw stem to hold the fastening members assembled, which nut is provided with 15 an opening 23 for registration with the opening 13, so that a cotter pin or key 25 may be passed therethrough to lock the nut against displacement. This pin is adapted to seat within notches formed in the nut to positively prevent the nut from working loose. It will thus be evident that the switch rails 20 will be firmly held in proper relative position in such a manner as to obviate liability

of loosening or disconnection of the parts under all ordinary conditions of service. 25

I claim:—

A connector for switch rails comprising a rod or bar having outer end portions forming seats for the rails and toothed portions adjacent thereto, angular bolts upon said toothed portions provided with screw stems, fastening members having toothed surfaces to interlock with the toothed surfaces of the rod or bar and longitudinally slotted for sliding engagement with the bolts, cuffs 30 apertured for the passage of said screw stems and engaging the sides of the toothed fastening members and the rod or bar, and nuts upon the screw stems and holding the aforesaid parts in position. 35

In testimony whereof I affix my signature in presence of two witnesses.

COMMODORE P. BAKER.
